1 Claim. (Cl. 94—48)

This invention relates to concrete surface treating devices and methods and more particularly to a device for tamping a concrete surface.

In the process of finishing concrete after the concrete is first deposited upon a subgrade from a mixing machine in a suitable manner it is necessary to subject the surface to a series of treatments to provide a smooth and finished surface. An extremely important surface treatment is a thorough and even tamping to displace the coarse aggregate a sufficient depth below the concrete surface and allow the fine materials to rise to the surface.

Since concrete contains coarse aggregate of varying sizes and shapes a desirable tamping treatment should include a provision for handling different size aggregate. In this way all of the aggregate, large and small, might be proportioned in the concrete at a sufficient depth to provide the desired even and smooth surface.

All presently known devices for tamping concrete surfaces suffer a single but significant disadvantage in that they are designed to handle only one size aggregate. A typical tamper consists of a metal grid which the operator continuously presses into the surface of the concrete to displace the coarse aggregate. The holes in the grid are of equal size which means that either they are too small for the larger size coarse aggregate or too large for the smaller size aggregate. In the case of a small size grid, the tamper has great difficulty in penetrating to any significant depth due to difficulty in pushing all sizes of coarse aggregate at once. In addition upward movement of the grid creates a suction force which draws the coarse aggregate up. In the case of a large size grid, the medium size coarse aggregate remains near the surface providing an uneven concrete surface. Regardless of the size of the grid, prior art tampers were unable to provide the proper depth of coarse aggregate. It is accordingly an object of this invention to provide a tamper for displacing coarse aggregate below the surface of concrete.

The tamping device of this invention tamps a concrete surface in a manner to provide a displacement of coarse aggregate below the surface of the concrete. A highly vertical penetration of the concrete is obtained by a tamper having a plurality of grid sections of varying size holes. A selected surface area is tamped in a series of steps with each area being successively subjected to a grid section of different size holes. In the first step the largest size aggregate is pushed downward from the surface leaving the medium and smaller size aggregate near the surface. In succeeding steps the smaller size aggregate is pushed downward. At the end of the operation on a selected area the coarse aggregate is displaced to a sufficient depth allowing the fine aggregate to rise to provide a smooth concrete surface.

It is therefore another object of this invention to provide an improved tamping device for displacing coarse aggregate below a concrete surface while allowing fine materials to rise toward the surface.

It is another object of this invention to provide a concrete tamping device which operates successively on different size coarse aggregate.

It is still another object of this invention to provide a concrete tamping device which impresses a grid of varying size holes on a concrete surface.

It is a further object of this invention to provide a concrete tamping device for achieving a highly vertical penetration of the concrete surface.

2

It is a still further object of this invention to provide a tamper which displaces coarse aggregate as it penetrates the concrete surface and allows fine aggregate to rise toward the surface without a suction effect on the coarse aggregate.

Other objects of the invention will become apparent from the accompanying specification read with the drawing, in which:

FIGURE 1 is a view in perspective of a tamper in accordance with one aspect of the invention.

FIGURE 2 is an elevation view of the tamper of FIG. 1 illustrating the operation of the tamper on a concrete surface, and

FIGURES 3a, 3b, and 3c are elevation views illustrating the step by step operation of a tamper according to the invention over a selected surface area.

According to a principal aspect of the invention there is provided a concrete surface treating device for tamping a concrete surface. The device comprises a plurality of grid sections, each having different size holes for displacing different size coarse aggregate. By a series of steps corresponding to the number of grid sections, a selected portion of a concrete surface is successively tamped by each of the different size grid sections. A highly vertical penetration of maximum depth is realized by each of the grid sections driving the coarse aggregate downward while causing the fine aggregate to rise. In this manner the coarse aggregate is displaced to a maximum depth below the concrete surface.

Referring now to the drawing and in particular to FIG. 1 there is illustrated a specific embodiment of the tamper of the invention. In the perspective view of FIG. 1 a tamper 21 consists of three grid sections 11, 12 and 13, each of which has successively smaller size holes commencing with the large holes of the section 11. The grid sections 11, 12, and 13 are integrally joined in a single structure which may be enclosed by a support frame 15. A handle structure 16 having a pair of vertically extending tubes 17 and 18 has its lower portion in the form of a pair of arcs 19 and 20 joining the ends of the support frame 15 by a suitable technique such as welding. The upper portion of the structure 16 may have a pair of handle bars 21 and 22 extending and adapted to fit the hands of an operator. The grid sections 11, 12, and 13 are successively greater in depth commencing with the section 11 which has the larger size holes. The grid sections 11, 12, and 13 preferably have square holes to minimize the exposed structural area. The sides forming the holes highly vertical. The grid sections may be constructed of a metallic material to provide strength and durability and may also be made of a plastic material to minimize the adherence of concrete to the sections.

As seen in the elevational view of FIG. 2 the grid section 11 has the largest size holes and the greatest depth with the succeeding sections 12 and 13 having progressively smaller holes and depth of penetration. The grid section 11 pushes coarse aggregate of large size below the depth A, while the sections 12 and 13 push aggregate to depths below B and C respectively. Thus the tamper 21 operates on varying sizes of aggregate with different depths of penetration.

Referring now to FIG. 3 there is illustrated in FIGS. 3a, 3b, and 3c, the successive tamping in a series of three steps of a concrete surface portion enclosed by P. The surface P is first penetrated by the tamper 21 in FIG. 3a with the grid section 11 penetrating the surface to a depth of A pushing the coarse aggregate of larger size than the holes in section 11 below the depth A. The smaller size coarse aggregate are not displaced. In the next step as seen in FIG. 3b the grid section 12 penetrates the portion P to a depth B pushing the middle

size coarse aggregate downward. The grid section **13** containing the smallest size holes penetrates the portion **P** during the final step pushing smaller size coarse aggregate downward below the depth **C**.

A significant advantage of the tamping device of the invention lies in the smooth concrete finish realized after the tamping. Because of the vertical sides of the grid sections and the depth of penetration of the larger grid sections, there is no suction on the concrete when the tamper is raised.

The embodiment illustrated shows a grid with cross-sectional sides forming holes. It is to be noted that if desired the grid may consist of parallel sides only with elongated holes equal to the length of the tamper being formed. Thus, the grid section **11** would comprise a number of vertical thin plates in parallel and spaced to displace the large size coarse aggregate. Grids **12** and **13** would have less depth and spacing to fit the smaller size aggregate.

Although the invention has been described and illustrated in detail, it is to be clearly understood that the same is by way of illustration and example only and is not to be taken by way of limitation, the spirit and scope of this invention being limited only by the terms of the appended claim.

I claim:

In a tamping device for treating a concrete surface, a plurality of grid sections joined to form a tamper, each of said grid sections having a predetermined depth of penetration when placed on said concrete surface, said grid sections joined to form successively different size holes and successively different depths of penetration in sequential alignment, each said grid sections having the largest size hole and longest depth of penetration being at one end of said device and said grid section having the smallest size hole and shortest depth of penetration being at the other end of said device, whereby when each grid section is applied to a selected portion of said concrete surface a different size of coarse aggregate is displaced to a different depth.
